UNITED STATES PATENT OFFICE.

CHESTER L. SHOBE, OF PERU, KANSAS.

DISTRIBUTOR AND TIMER COMBINED FOR INTERNAL-COMBUSTION ENGINES.

Application filed August 15, 1922. Serial No. 582,023.

To all whom it may concern:

Be it known that I, CHESTER L. SHOBE, a citizen of the United States, residing at Peru, in the county of Chautauqua and State of Kansas, have invented certain new and useful Improvements in Distributors and Timers Combined for Internal-Combustion Engines, of which the following is a specification.

10 This invention relates to timers and distributors for internal combustion engines and the primary object of the invention is to provide a combined distributor and timer which is arranged as to form a unitary mechanism, in which a single rotating element is utilized for making and breaking the contacts between the primary and secondary circuits, thereby effectively decreasing the complexity of timer-distributors and 20 eliminating a number of parts now utilized in the ordinary timer-distributor forms.

Another object of the invention is to provide a novel combined timer-distributor, in which the rotor for the distributor is utilized 25 for the timer for making and breaking the timer contacts, the improved construction forming a positive means for making and breaking the primary circuit and dispensing with the necessity of utilizing platinum 30 points, in the timing mechanism, the improved timing mechanism eliminating sparking between the contact points.

A further object of the invention is to provide a novel mechanism for making and 35 breaking the primary circuit, the rotor carrying an improved contact point for engaging the stationary contact points of the timer, the means for mounting the movable contact point on the rotor permitting a quick 40 contact to be had between the movable contact and the stationary contacts, the means for mounting the movable contact on the rotor including a substantially annular shaped split spring, which permits the movable 45 contact to give for engaging the stationary contacts and then spring past the same with a quick action.

A further object of the invention is to provide a combined timer-distributor embodying a single housing including the stationary plate through which the timer-distributor shaft extends and a non-electric conducting shell for receiving said shaft, the shell carrying the contacts for the primary circuit and the contacts for the secondary circuit in which the spark plugs are in-

corporated, the rotor carried by the operating shaft being formed of insulating material and carrying a novel means for engaging both the timer contacts of the primary circuit and novel means for engaging the contacts of the secondary circuit for distributing the current to the spark plugs.

A further object of the invention is to provide an improved timer-distributor of the above character, which will be durable and efficient in use, one that will be simple and easy to manufacture, and one which can be placed upon the market at a reasonable cost.

With these and other objects in view the invention consists in the novel construction, arrangement and formation of parts, as will be hereinafter more specifically described, claimed and illustrated in the accompanying drawings forming a part of this specification, in which drawings

Figure 1 is a horizontal section through the improved timer-distributor taken on the line 1—1 of Figure 2.

Fig. 2 is a vertical section through the improved timer-distributor taken on the line 2—2 of Figure 1.

Fig. 3 is an enlarged horizontal section through the rotor for the timer-distributor taken on the line 3—3 of Figure 2, the view illustrating the novel means for connecting the rotor on the operating shaft.

Referring to the drawings in detail, wherein similar reference characters designate corresponding parts throughout the several views the letter A generally indicates the improved combined timer-distributor, which includes the housing B which receives the timer shaft C.

The housing B includes a disc shaped lower wall or bed plate 5, the axial center of which carries the depending sleeve 6 for the reception of the timer shaft C. This sleeve 6 is of course secured in any preferred manner to the casing or bearing 7 for the said shaft C. The upper face of the bottom wall or bed plate 5 is provided adjacent and in spaced relation to the periphery thereof with an upstanding flange 8 which forms in connection with the said wall 5 and a seat 9 for the reception of the shell 10 of the said housing B. This shell 10 is formed of insulating material, such as hard rubber, fiber or the like and includes the annular side wall 11 and a dome shaped top wall 12. The top wall 12 at its axial center is pro-

vided with a sleeve 13 for supporting the central or high tension terminal from the secondary coil as indicated by the reference character 14 and this terminal supports the 5 depending central contact 15. Disposed in annular formation about the top wall 12 are the sleeves 16 which support the terminals for the wires, indicated by the reference character 17 and leading to the spark plugs 10 18 indicated diagrammatically in Figure 2 of the drawings. These sleeves of course support the depending inwardly extending contacts 19. It is to be understood of course that there are as many contacts 19 as there 15 are spark plugs required and in the form shown the timer-distributor is for a four cylinder engine and thus there are four of the contacts 19, which are arranged at quarters in the housing. 20 The timer shaft C is driven from the engine in any preferred manner and extends axially within the shell or housing B through the sleeve 6 and has its upper end provided with a polygonal extension 20 which supports the rotor D for the timer-distributor. The intensity of the spark may be advanced or retarded in the ordinary manner by an arm or a lever (not shown) attached to the breaker housing. Directly below the polygonal extension 20 of the shaft C a collar 21 is fitted thereon for engaging the bottom wall 5 to prevent displacement of the shaft from out of the shell.

The rotor D comprises a hub 25 formed 35 of insulating material and the hub at its axial center is provided with a polygonal opening 26 for the reception of the polygonal end 20 of the shaft C. The upper end of the hub 25 has formed integral therewith 40 a radially extending arm 27 which constitutes the means for carrying the rotatable contact 28 for the distributor. Disposed at the opposite side of the hub 26 is the rotatable contact 29 for the timer mechanism and 45 this contact 29 is disposed at an angle of substantially 20° to the radial line which bi-sects the arm 27. This arrangement is so made as to permit the correct operation of the timer and distributor mechanism. The 50 hub 25 at one side of the polygonal opening 26 is provided with a pocket 30 which communicates with said polygonal opening and in this pocket is adapted to be positioned a leaf spring 31 which bears against the shaft 55 20 and forms a ground for the contact 29, as will be hereinafter more fully described. It can be seen however that the spring 31 is provided with an attaching portion 32 which is anchored in the hub adjacent to the 60 periphery thereof.

The arm 27 has secured thereto as at 33 a suitable strip of conducting material 34 the outer end of which is provided with a head 35, that is adapted to engage or contact with 65 the stationary contacts 19 carried by the

shell 10 for distributing the current to the spark plugs. The inner end of this strip 34 is provided with a resilient extension 36 which is adapted to contact at all times with the central contact 15 carried by the shell. 70

The movable contact 29 for the timer is supported by an annular shaped split spring 37 which is secured to the hub for contact with attaching base 32 of the spring 31 by suitable screw 38. The spring 37 diametrically opposite the screw 38 has anchored therein in any preferred manner a screw 39 on which is threaded the movable contact 29 and this contact is held in any preferred adjusted position on the screw 39 by means of 80 a nut 40. It is obvious that as wear takes place on the timer contacts that the contact 29 can be adjusted on the screw. This contact 29 has an arcuate outer face 41 and is in the nature of a shoe to form a wiping 85 contact with the stationary contacts 42.

The contacts 42 are arranged at quarters on the side wall 11 of the shell 10. These contacts 42 are disposed intermediate the contacts 19 of the secondary circuit. The 90 stationary contacts 42 are held in position on the side wall 11 of the shell 10 by means of suitable stems 43 which are extended through openings 44 in the side wall and these stems have threaded thereon suitable 95 retaining nuts 45. One of the stems 43 forms a binding post for the wire 46 which leads from the primary winding of the coil unit 47. It can be seen that in operation the shoe or movable contact 29 will engage 100 one of the contacts 42 and the spring 37 will give to such extent that as the shoe rides past the stationary contact, the spring will quickly move the shoe from out of engagement with the stationary contact thus making a quick contact which is so desirable in timing mechanisms. 105

Referring to Figure 2 of the drawings in which is shown the circuit diagrammatically for the improved timer-distributor it 110 can be seen that a wire 48 is connected with a feed wire 49 leading from a suitable source of electrical energy such as a storage battery 50 and this wire 48 is connected to one terminal 51 of the primary coil of the inductance coil unit 47. The wire 46 herebefore mentioned, which is connected with one stationary contact 42 is connected with the other primary terminal 52 of the coil 115 47. The wire 48 can have interposed therein a suitable resistance unit 53 if so desired. A suitable control switch 54 can also be interposed in this wire if so desired. It is to be also noted at this point that all of the stationary contacts 42 of the timing mechanism are electrically connected together by an annular conducting strip 42'. This strip can be imbedded within the side wall 11 of the shell 10 as clearly shown in Figures 1 and 2 of the drawings. The other 120 125

terminal of the battery 50 is grounded to the body of the vehicle as indicated by the reference character 55. The wire 48 is also connected, as in the usual construction, 5 with the generator 56 which also has its opposite terminal grounded as at 57. The wire 48 intermediate the battery and generator has incorporated therein the usual regulator or automatic cut out 58. A wire 59 is electrically connected with a central terminal 14 of the distributor and is connected as at 60 with one terminal of the secondary winding. The other terminal of the secondary winding is grounded as indicated by the 15 reference character 61. The distributing contacts 19 are connected as heretobefore stated by wires 17 with one terminal of the spark plug indicated by the reference character 18. The other terminal of the spark 20 plugs are grounded of course to the engine in the ordinary manner as indicated by the reference character 62.

In operation of the improved timer-distributor it can be seen that when the primary contacts 29 and 42 are separated a high voltage current is introduced in the secondary winding of the coil 47 which blows in the center contact 15 of the distributor and is collected by the contact strip 34 and distributed to the contacts 19 from whence it jumps the gaps of the spark plug 18. It is of course to be understood that the plugs are fired in proper sequence by the contacting of the brush or strip 34 with the contacts 19.

From the foregoing description it can be seen that an improved timer and distributor has been provided, which is of exceptionally simple and durable structure and which 49 eliminates a number of parts generally employed in timer-distributor forms and which permits the positive operation of the timing and distributing mechanism.

Changes in details may be made without departing from the spirit or the scope of this invention but what I claim as new is:

1. In a combined timer and distributor, a shell including a base plate, a cap formed of insulating material fitted upon the base plate, a timer shaft extending into the shell through said base plate, a rotor formed of insulating material secured to said shaft and arranged in said shell, a plurality of primary contacts anchored to the cap and arranged in annular formation, an annular strip of conducting material anchored in

said shell and connected with said primary contacts, a contacting shoe arranged to engage the primary contacts, a resilient ring connecting the shoe to the rotor, means electrically connecting the contacting shoe with the shaft, a radially extending arm formed of insulating material carried by the rotor disposed opposite to the contact shoe and arranged at an angle of substantially 20° to the radius line of the contact shoe, a plurality of secondary contacts connected with the spark plugs of an engine to be controlled, arranged in annular formation and carried 60 by said shaft and disposed at quarters thereon and arranged intermediate the primary contacts, a central contact carried by the shoe, a resilient strip carried by the arm engaging the central contact, and a wiper head connected with said conducting strip 65 for engaging the secondary contacts.

2. In a rotor, a hub formed of insulating material and having a socket for receiving a timer shaft, a contact shoe, a resilient carrier of conducting material for said shoe, a spring element of conducting material carried by said hub and positioned for engaging a timer shaft extending into the socket and frictionally holding the hub upon the 80 shaft, and means for securing the carrier and spring element to the hub in contacting engagement with each other.

3. In a rotor, a hub formed of insulating material having a socket formed therein, 85 for the reception of a timer shaft, a pocket formed in said hub communicating with said socket, a contact spring anchored in the hub and fitted in said pocket for engaging said shaft, a contact shoe having a threaded 90 socket therein, a spring secured to the hub and connected with said contact spring, a screw anchored to said spring and arranged to fit in said socket of said shoe to permit the shoe to be adjusted to different positions in relation to the hub, and a nut 95 threaded upon said screw for holding the shoe in an adjusted position on said screw.

4. In a rotor, a hub formed of insulating material having a socket formed therein for the reception of a timer shaft, a pocket formed in said hub communicating with said socket, a contact spring anchored in the hub and fitted in said pocket for engaging 105 said shaft, a contact shoe, a resilient ring carrying the contact shoe, and a fastener securing said ring to said hub in engagement with the contact spring.

CHESTER L. SHOBE.
